UNITED STATES PATENT OFFICE.

LEE HOWARD SIMMONS, OF GOLDSBORO, NORTH CAROLINA, ASSIGNOR TO SIMMONS
FORCED DRAFT COMPANY, OF GOLDSBORO, NORTH CAROLINA, A CORPORATION
OF NORTH CAROLINA.

FURNACE-GRAVE.

1,321,252.

Specification of Letters Patent. Patented Nov. 11, 1919.

Application filed April 20, 1918, Serial No. 229,673. Renewed September 27, 1919. Serial No. 326,927.

To all whom it may concern:

Be it known that I, LEE HOWARD SIMMONS, a citizen of the United States, residing at Goldsboro, in the county of Wayne 5 and State of North Carolina, have invented certain new and useful Improvements in Furnace-Grates, of which the following is a specification.

My invention relates to a new and useful improvement in furnace grates and particularly to the shaker form of grate.

An object of my invention is to provide a furnace grate that consists of a plurality of grate bars, arranged in two series, the 15 number depending upon the heating area desired. These grate bars in turn are each provided with a plurality of fire bars, all of the fire bars in each grate bar being so arranged that they may be simultaneously 20 shaken and, by arranging the grate bars in series, it is possible to shake all the fire bars in any series of grate bars at the one time. In other words, the grate bars are preferably arranged in two series, that is 25 left and right series and means are provided to shake all the fire bars simultaneously in the left series or in the right series.

Another object of my invention is to provide a furnace grate having a plurality of 30 grate bars arranged in series and wherein each grate bar is in reality but a hollow frame in which rest a plurality of fire bars. By constructing the grate bars as shown 35 a large amount of metal is saved and they are much less expensive to manufacturer than a grate bar that is more than simply a frame.

Still another object of my invention is to provide a grate bar having spaced fire bars 40 located therein so that if any of the fire bars become damaged by the intense heat, it is a very simple matter to simply remove the damaged fire bar and insert a new one in the grate bar, and in the same way, if 45 it so happens that any one of the grate bars is damaged it is but a simple matter to remove the same and insert a new one.

Still another object of my invention is

to provide a shaker grate comprising a plurality of grate bars provided with a plurality of fire bars located therein and each grate bar so arranged that it is possible to rock or shake all the fire bars in the said grate bars at one time and also hold them in locked position at the end of the shaking movement.

Still another object of my invention is to provide a furnace grate of the class above mentioned wherein it is possible to rock every fire bar in one series of grate 60 bars with the one movement of an operating or shaking lever and to lock every fire bar in the one series of grate bars when desired.

Still another object of my invention is to provide a grate bar that is in reality but 65 a hollow frame having bearing points near its opposite ends for the reception of a rocking member to agitate or rock or shake the fire bars located in the grate bar and also to hold them in a locked position.

With these and other objects in view which will appear as the specification continues, my invention consists in certain new and novel features and combinations of parts as will be hereinafter more fully described and pointed out in the claims.

Referring now to the drawings,

Figure 1 is a top plan view with a few 75 of the fire bars in position and the wall of the furnace in section.

Fig. 2 is a front elevation showing one set of bars in section and the other in elevation, the set of bars in section being shown in the rocked or tilted position.

Fig. 3 is a side elevation taken just in side of the outer wall.

Fig. 4 is an enlarged sectional view taken through one of the grate bars on line 4-4 of Fig. 1 and showing a fire bar in locked position.

Fig. 5 is a similar view but showing a fire bar in raised or shaking position.

Fig. 6 is an enlarged side elevation of one of the rocker bars.

Fig. 7 is an end view taken from the left 95 of Fig. 6.

Fig. 8 is also an end view taken from the right of Fig. 6, and

Fig. 9 is a side elevation partly in section of one of the grate bars.

Referring now to the drawings and for the moment to Fig. 1, an installation of my furnace grate is shown wherein a furnace wall 1 is shown which is of any desired depth, and set in this wall are the two end supporting bars 2 and 3 and a central supporting bar 4 on which bars the plurality of grate bars 4' are designed to rest. These grate bars are preferably arranged in two series such as 5 and 6 and in Fig. 1 I have shown five grate bars in each series.

It is to be understood however that if a greater heating area is desired a number of grate bars may be added to both series. These grate bars 4' forming the two series 5 and 6 are rectangular in shape and each comprises the two side walls 7 and 8 with the end walls 9 and 10. A reinforcing strip or brace 11' is located about centrally of each grate bar which connects the side walls 7 and 8 to snugly brace the same. Each grate bar is provided with four spacing lugs 11, two of which are located on the side wall 7, the other two being located on the side wall 8, these lugs 11 being spaced a slight distance from the end walls 9 and 10.

By providing each grate bar with these spacing lugs 11 the adjacent grate bars are held a slight distance apart, the spacing lugs on one side contacting with the spacing lugs on the side wall of the adjacent grate bar, thus allowing a certain amount of circulation of cold air from beneath the grate bars to keep them from being damaged by the heat of the fire.

As the grate bars are all similar, a description of one will be sufficient to understand their construction.

Referring now for the moment to Fig. 9, it will be seen that the one end wall 9 projects slightly below the level of the bottom of the bar forming a lug as at 12, so that this projection 12 will fit within one of the slots or openings 13 formed longitudinally of the supporting bar 4 to retain the bar in its set position. The other end wall 10 of the grate bar does not extend below the bottom of the bar as this end simply rests either on the supporting bar 2 or on the supporting bar 3 depending in which series it is placed.

Spaced a short distance from each of the walls 9 and 10 is a downwardly extending flanged portion 14 clearly shown in Figs. 2, 3, 4, 5 and 9. These flanges are provided with openings 15 which form bearing points for the support of a rocker bar 16 which will be hereafter described. A slight opening 17 is left between the wall 9 and the flange por-

tion 14 so that any ashes or dust that fall into the openings 15 will not collect or clog 65 there but may work or drop through the opening 17 down into the ash-pit. This arrangement is followed at both bearing points in the grate bar as clearly shown in Fig. 1.

Located in each grate bar is a plurality 70 of fire bars 18 and as a description of one is a description of all, only one will be described for the present.

Referring now to Figs. 4 and 5, one of these fire bars 18 is clearly shown which extends completely across the grate bar 4' and for a distance beyond the side walls 7 and 8. This fire bar 18 is of a relatively small transverse thickness (see Fig. 1) so that a number of them can be located transversely 80 in each grate bar. This fire bar 18 is also provided with spacing lugs 19 on one side thereof, which lugs contact with the adjacent bar on the left to slightly space the fire bars one from another.

The fire bar 18 is also provided with two downwardly extending flanges 20 and 21, the flange 20 being provided also with an inwardly extending lug or projection 22. These two flanges leave a rectangular space 90 23 which space is greater at the right side than at the left, as the projection 22 extends into the same. The outer edges of the two flanges 20 and 21 also limit any transverse movement of the fire bars in the 95 grate bar.

Referring now to Figs. 4 to 8 inclusive, a rocker bar 16 is shown, one of these bars to be placed in each of the grate bars. This rocker bar 16 consists of a web portion 24 100 and an elliptical upper contacting portion 25. This rocker bar 16 is reinforced as at 26 or in other words, the upper portion 25, the web portion 24 and also the remaining portion 26 form substantially a rail or I- 105 beam construction.

The right end of this rocker bar 16 is transversely flanged and extends downwardly as shown at 27 and in this end portion is formed one trunnion 28 extending outwardly and on the inner portion and below the trunnion 28 is a further trunnion 29 which extends inwardly. The left side of this rocker bar 16 also is flanged and projects downwardly as at 30 and on the outer surface thereof is a trunnion 31. This trunnion however is located opposite the trunnion 28 or in other words in the same parallel plane. These two trunnions 28 and 31 are designed to rest in the bearing 15 formed 115 in the downwardly depending flanges 14 of the grate bars heretofore mentioned.

By glancing at Figs. 7 and 8 the relative length of the right and left ends 27 and 30 of the rocker bars 16 may be clearly seen. 125 The extra pin or trunnion 29 on the right

end 27 of each of the rocker bars 16 is for the purpose of fitting within a bar 32, so that all the rocker bars in an entire series may be moved by the movement of this bar 32.

By connecting all the rocker arms 16 to the shaker bar 32 a movement of this bar will move all of the rocker bars 16 in the series, which in turn move or shake the fire bars 18 which shaking movement will be shortly referred to.

Glancing at Figs. 4 and 5 again for the moment, it will be seen first that in Fig. 4 the rocker bar 16 is in a locked position, that is, as this rocker bar is mounted eccentrically with relation to the fire bar in a grate bar, when in a left handed tilted position, as shown, the lower surface of the elliptical or upper portion 25 of the rocker bar 16 will contact with the upper surface of the projection 22, thereby holding the fire bar 18 against any upward movement, and likewise every fire bar in the grate bar.

The height of the rocker bar 16 is such that when the shaker bar 32 is moved outwardly or to the left with regard to Figs. 4 and 5, the rocker bar 16 in assuming an upright position will force the fire bar 18 upwardly at one end, raising it completely off one of the side walls as shown in Fig. 5. That is, the radius of the rocker bar 16 from the bearing point 15 and the upper surface of the contact portion 25, is greater than the distance between the defining upper edge of the space 23 of the fire bar and a line drawn to the center of the bearing point 15, so that, when the rocker bar 16 is in an upright position as shown in Fig. 5, one of the ends of the fire bar will be raised from the side walls. Either end of the fire bar 18 might be raised depending on the weight on the said fire bar. It will be seen that if one end of the fire bar was more weighted than the other, the end meeting with the less resistance would be raised. The fire bar 18 is bound to be tilted when the rocker bar 16 is in an upright position as shown in Fig. 6 but which end will be tilted depends upon the weight on the fire bar; some may therefore tilt in one direction while others, at the same time, will tilt in the other direction. Forcing the lever 32 to the right, as regards to Figs. 4 and 5, will return the rocker bar 16 to the position shown in Fig. 5 thereby again locking the fire bar 18 shown, and of course all others in the grate bar.

Referring for the moment to Figs. 1, 2 and 3, it will be seen that this bar 32 is connected by a clamp 33 to a rod 34 which in turn is operated by a handle 35 which is fulcrumed to a base or support 36. By providing this clamp the length of travel of the

shaker bar 32 with relation to the movement of the handle is established, so that the movement of rocker bars 16 in turn will be limited. Transverse movement is allowed for as may be seen by comparing the position of the fire bars in Figs. 4 and 5.

There are two handles 35, one for each series of grate bars and rocker bars similar in all respects to each other, one for operating all of the fire bars located in the grate bars forming series 5 and the other for operating all of the fire bars in the grate bars in series 6.

From the foregoing it will be seen that my grate consists of two series of grate bars, which bars are in turn provided with a plurality of spaced fire bars, and located in each fire bar is a rocker bar, which is eccentrically mounted with regard to the fire bars so that movement of the said rocker bar causes the fire bars on the grate bars to be tilted some from one end and some from another when said rocker bar is forced to an upright position, and which rocker bar, by its construction, will also retain all of the fire bars in a locked position when said rocker bar is in an angular or tilted position. Each of the rocker bars in the series is connected to a shaker bar which is, in turn, connected by a clamp to a rod operated by a handle so that a movement of the handle will tip or rock every fire bar in the grate bars in the one series; and a movement of the other handle will likewise tip or rock all the fire bars in the grate bars arranged in that series. A fine shaking movement is therefore obtained and with but a few operations of the handles the fire bed will be greatly agitated.

It will also be seen that my grate bars are exceedingly simple in construction each comprising but side walls and end walls, spacing lugs and depending flanges near its opposite ends in which are formed bearing points for a rocker bar. Likewise the fire bars are simple in construction and cheap to manufacture and are so constructed in their under portion that they may be tilted by movement of the rocker bar or may be held tightly in a locked position when so desired. Also that it is a simple matter to replace one or all of the grate bars and likewise a simple matter to replace one or all of the fire bars.

The grates are especially adapted for the use of fine or pulverized fuel although a coarser grade may be used if necessary. My entire grate is one that is very efficient in service and has been successfully used under 700 horse-power boilers.

Many slight changes may be made in the construction of the grate without in any manner departing from the spirit and scope of the invention.

Having thus described my invention what I claim as new and desire to secure by Letters Patent, is:

- 5 1. A furnace grate comprising in part a grate bar formed with end and side walls and open at its top and bottom, depending flanges near its opposite ends and bearing points formed in said depending flanges, fire bars located in said grate bar and arranged transversely thereof, a rocker bar 10 pivotally mounted in the bearings in said depending flanges to agitate said fire bars with relation to the grate bar when said rocker bar is operated.
- 15 2. A furnace grate comprising in part a hollow grate bar, two side walls and end walls, one of the end walls provided with a downwardly extending lug thereon, two downwardly extending flanges formed near 20 the ends of said grate bar and provided with two cut out portions to form bearing points for a rocker bar, the cut out portions extending beyond said depending flange to form an opening.
- 25 3. A furnace grate comprising in part a hollow grate bar having side and end walls and spacing lugs formed on said end walls, two downwardly extending flanges extending between said side walls and located 30 near the ends of said grate bar, said flanges provided with openings therein to form bearing points, a plurality of transversely positioned fire bars located on the upper portion of said side walls and an eccentrically mounted rocker bar in said grate bar for raising the said fire bars when said rocker bar is moved to an upright position.
4. A furnace grate comprising in part a grate bar consisting of side and end walls 40 and depending flanges extending from the side walls, said downwardly extending flanges located near the two end walls, said flanges provided with bearing points for the reception of a rocker bar, a plurality of fire bars located in said grate bar and resting on the two side walls, a rocker bar mounted in said downwardly extending flanges, said rocker bar being eccentrically mounted so that when moved to an upright 45 position said fire bars will be raised from one of the said walls of said grate bar and said rocker bar so constructed as to hold said fire bars in a locked position when said rocker bar is moved to a tilted position.
- 55 5. A furnace grate comprising in part a hollow grate bar, fire bars located transversely in said grate bar, said fire bars provided with downwardly extending flanges and one of said flanges provided with an inwardly extending lug, a rocker bar eccentrically mounted in said grate bar and adapted to tilt said fire bar when in an upright position, the upper portion of said 60
- 65 rocker bar adapted to contact with the inwardly extending lug formed on the flange of said fire bar to hold the said fire bar in a locked position when said rocker bar is in a tilted position.
- 70 6. A furnace grate comprising a hollow grate bar, a rocker bar eccentrically mounted in said grate bar, fire bars located in said grate bar and arranged transversely thereof, said rocker bar having an I-shaped head, said fire bars provided with downwardly extending flanges and one of said flanges provided with an inwardly extending lug, the said lug adapted to be held by said rocker bar when said rocker bar is in a tilted position and said fire bars adapted to be raised in said grate bar when said rocker bar is in a vertical position.
- 75 7. A furnace grate comprising in part a grate bar, a rocker bar mounted within said grate bar and fire bars located transversely of said rocker bar, the radius of said rocker bar being greater than the distance between the bearing point of said rocker bar and the under portion of said fire bar so that said fire bar will be moved when said rocker bar is operated.
- 80 8. A furnace grate comprising in part a grate bar provided with downwardly extending flanges and provided with openings for the reception of a rocker bar, fire bars located in said grate bar and adapted to be tilted when said rocker bar is swung to a vertical position and said fire bars adapted to be tightly held in said grate bar when said rocker bar is moved to a tilted position.
- 85 9. A grate bar comprising end walls and side walls and a rocker bar in said grate bar, fire bars located in said grate bar and provided with downwardly extending flange portions and an inwardly extending lug on one of said flange portions, said rocker bar having an enlarged head at its upper end and said head adapted to rest on said inwardly extending lug when said rocker bar is forced to a tilted position and the said fire bars adapted to be raised and shaken when said rocker bar is forced to a vertical position.
- 90 10. A furnace grate comprising a plurality of series of hollow grate bars, a shaker bar located under each of said series of hollow grate bars, a rod connected to each of said shaker bars and a handle connected to each of said rods, fire bars located in said grate bars and arranged transversely thereof, a rocker bar pivotally mounted in each of said grate bars, the rocker bars in one series connected to one of said shaker bars and the rocker bars in the other series connected to the other of said shaker bars, said rocker bars being so mounted that when 100
- 105 110 115 120 125

forced to an upright position the said fire bars will be raised with regard to said grate bars and said rocker bars arranged to lock with said fire bars when said shaker bars are forced inwardly.

11. A furnace grate comprising a plurality of hollow grate bars, a plurality of fire bars located in each of said grate bars, means for tilting said fire bars with relation to said grate bars, the said means capable of tilting some of the bars from one end and the other of said bars from the other end.

12. A furnace grate comprising a plurality of grate bars, a plurality of fire bars located in each of said grate bars and arranged transversely thereof, said fire bars capable of a slight transverse movement in said grate bars, means for tilting said fire bars within said grate bars and said fire bars being capable of being tilted from either of their ends.

In testimony whereof I affix my signature.

LEE HOWARD SIMMONS.
